UNITED STATES PATENT OFFICE.

DONALD M. SIMONS, OF OSBORNE, PENNSYLVANIA, ASSIGNOR TO STANDARD UNDER-GROUND CABLE COMPANY, OF PITTSBURGH, PENNSYLVANIA, A CORPORATION OF PENNSYLVANIA.

CABLE JOINT.

Application filed August 5, 1925. Serial No. 48,301.

My invention relates to improvements in cable joints. In an application for Letters Patent of the United States, filed November 19, 1924, Serial No. 750,740, I have described the building of an extension of the surface of an electrode, such as to give greater security against break-down of insulation. Circumstantially, I described that invention in application to a cable-joint, and showed a joint in which my present invention also is embodied. In other prior and still pending applications, Serial No. 738,424, filed September 18, 1924, and Serial No. 743,645, filed October 15, 1924, I describe more specific applications to joint building of the invention of the first-mentioned application. In this application I seek protection of the joint structure, as such.

My invention is illustrated in the accompanying drawings. Fig. I is a view in medial and longitudinal section of a cable joint, having my invention embodied in it. Fig. II is a diagrammatic view in plan, of a web of material employed in building the joint of Fig. I, and it is so placed relatively to Fig. I as to indicate how application is made. Fig. III is a view, corresponding to Figs. I and II, showing a cable joint in the building of which my invention is employed in somewhat greater elaboration.

In Fig. I, I show two cable ends, from which the sheaths 1 have been cut away, exposing the envelopes 2 of machine-laid insulation, and from which the envelopes of insulation in turn have been cut away, exposing the conductors 3. The conductors are electrically united, as by the sweated-on sleeve 4 of metal, and the problem is properly and adequately to insulate this union within the joint casing 5.

In Fig. I the machine-laid insulation of the cable to be united is cut away in opposite successions of steps. The conducting sleeve 4 and the adjacent reaches of bare cable are suitably enveloped in insulation to the level of the first step of machine-laid insulation, and upon the continuous surface so afforded I wrap insulation.

My invention consists in providing a web of insulating material of such width as to extend across the interval, from edge to edge of the cut-away bodies of insulation 2,

and of proper length, whether in a single piece or in a succession of pieces; and in applying the web in a single wrap, filling all the space between the cut ends, and restoring throughout the interval the original diameter of the insulated conductor.

Preferably I provide a web which shall immediately envelope the conducting sleeve 4 and the adjacent reaches of otherwise bare conductor and shall in continuous wrap fill all the interval between the stepped ends of the two bodies 2 of machine-laid insulation. The structure is sufficiently shown in Fig. II, and its position relatively to the structure of Fig. I will indicate how the web is shaped and applied. The web 6 is stepped along its edges according to the stepped conformation to which it is to be applied. At its narrow end it is of precisely the width to fit between the innermost or lowest steps of the two bodies 2 of insulation. At its narrow end it may be cut away, as at 7, to make provision for the filling in of the spaces between the sleeve 4 and the adjacent innermost steps of the bodies 2. The web is of such length and the steps to which it is shaped are individually of such length as to fill the interval between each opposite pair of steps in the bodies 2, pair after pair, as wrapping progresses. And by wrapping in the manner indicated I produce a body 8 of insulation, of the character indicated, filling all the interval between the cut-away ends 2 of machine-laid insulation.

The application of web 6 must of necessity be made in the field. The old way was to use tape of less width and to apply it helically turn upon turn, progressing from one side of the interval to the other, and back again, till the whole space was filled. By my invention of a web of the full width of the interval, applied in a single wrap, I first of all attain a denser structure, of greater dielectric value, a matter of first importance, particularly in high-tension installations. In addition to that my invention admits of expedition in making installations in the field.

In a companion application in which I am joint applicant with Frank D. Barbour apparatus is described and claimed for applying to a cable joint the web of my present invention, and with such apparatus par-

ticularly, the web may be applied in a very short space of time, and with the greatest precision and closeness of fit of wrap.

The web will ordinarily be of paper. It 5 may be formed of equivalent material, muslin, for instance. It will ordinarily be already filled with a suitable insulating compound, such as oil or varnish.

Such a web may be of a maximum width 10 of thirty inches, say—I give only exemplary figures: I am not meaning to limit myself to particular dimensions. The wrap itself when applied may be one inch deep. And, to achieve this, the initial web may be a hundred feet long. The advantage of handling by machinery such a web of material, will be apparent.

The machine may be provided with knives which from a roll of maximum width cuts 20 the web accurately to size as application is about to be made. This feature is fully explained in the specification of the companion application.

I have already intimated that while the 25 web of material may be integral from end to end, it may on the other hand be made up of a succession of lengths, and it will be understood that, while the web may so be discontinuous in length, the components will still be applied in succession and being applied will extend in a single convolution, throughout the so built up body of insulation.

When the web has been applied and the interval between the bodies 2 of insulation has so been filled the joint may otherwise be completed as desired. The whole is enclosed in the usual casing 5, secured at its ends to the cable sheath. At any suitable 40 time before completion or on completion, the joint structure may be flushed and filled with insulating compound, and the wrapped-on body of insulation may be so flushed, whether or not the web of material had 45 before application been filled with such material.

The web 6 of applied insulation may as is explained in the first of the applications mentioned above be the carrier of a metal strip, to achieve the ends there described.

In Fig. III I show a cable joint in which the spaces between the cut-away ends of the machine-laid insulation are filled, precisely as in the joint illustrated in Fig. I. Of the joint of Fig. I I said that externally of the wrapped-on body 8 of insulation, applied as described, the spaces within the joint casing might be filled in any desired manner. In Fig. III I show that these external spaces may be filled by a continuation of the wrap, 60 and it is apparent that the prolonged web will in this case be of such width and of such marginal shape as to produce in a continuing wrap the added body of insulation 65 9. Furthermore, the edges of this extension of the web may carry metal strips, to afford, when the web has been applied, electrical extensions 10 of the cut-away ends of the cable sheath, thus effecting the purposes set forth in applications, Serial Nos. 738,424 and 743,- 70 645, alluded to above. The edges of the webs will be stepped to still greater width, to form the innermost turns of body 9, and from that point the width of the web may diminish, to achieve the particular shape 75 which in Fig. V the body 9 is shown to possess. Further description is deemed unnecessary.

I claim as my invention:

In a cable joint two cable ends with their 80 envelopes of machine-laid insulation cut away in a succession of opposite and receding steps, their conductors united, and the union surrounded and the interval between the bodies of machine-laid insulation filled 85 with a wrapped-on web of sheet insulation of the full width of the interval and laid in a single wrap.

In testimony whereof I have hereunto set my hand.

DONALD M. SIMONS.
